[57] **CLAIM**

The ornamental design for a food preparation and storage device, as shown and described.

DESCRIPTION

FIG. 1 is a perspective view of a food preparation and storage device embodying my design from above;
 FIG. 2 is a perspective view thereof from below;
 FIG. 3 is a front view thereof, the back view being identical;
 FIG. 4 is a left side view thereof, the right side view being identical;
 FIG. 5 is a top view thereof; and,
 FIG. 6 is a bottom view thereof.
